UNITED STATES PATENT OFFICE

2,057,180

CARTON

Edward C. Berg, Chicago, Ill., assignor to Ace
Carton Corporation, a corporation of Illinois

Application October 1, 1934, Serial No. 746,290

12 Claims. (Cl. 229—11)

The present invention is directed generally to cartons or paper containers, but more particularly to a novel and improved carton of the tray type which is adapted to contain therein fragile or crushable merchandise.

One of the objects of the present invention is to provide a novel and compact and relatively strong tray type carton for holding merchandise of fragile nature in separated or spaced-apart position.

10 A further object of the invention is to provide an improved tray-type carton in which the merchandise therein is completely protected at all times and from which the merchandise may be easily removed therefrom.

15 A still further object of the invention is to provide a novel and improved carton for the merchandising of fragile or crushable articles in which the tray thereof consists essentially of a plurality of perforated mats. The perforations in these mats are held in registering alignment and the mats held in compact position by the carton itself, thereby eliminating the necessity of gluing or otherwise securing these perforated mats together as heretofore required.

20 25 A still further object of the invention is not only to provide a novel and improved carton of the tray or partition type for holding fragile merchandise therein, but also a novel form of a scored protective flap which is detachably secured to one end of the carton and lies over the top of the tray for protecting the merchandise. This flap is easily lifted by folding on the scored portions so that easy access to the material in the carton may be had.

30 35 These and other objects are accomplished by providing a construction and an arrangement of the various parts in the manner hereinafter described and particularly pointed out in the appended claims.

40 Referring to the drawing:

Fig. 1 is a perspective view of my complete improved carton;

Fig. 2 is a cross-sectional view taken on the line 2—2 in Fig. 1;

45 Fig. 3 is a longitudinal cross-sectional view showing the tray partly telescopically removed from its enclosing member and with the protective flap raised so that access to the material in the tray may be had;

50 Fig. 4 is a fragmentary top plan view with a portion broken away to show the construction of the various parts;

55 Fig. 5 is an enlarged cross-sectional view taken on the line 5—5 in Fig. 4;

Fig. 6 is an enlarged cross-sectional view taken on the line 6—6 in Fig. 4;

Fig. 7 is a cut-out flat blank of the internal carton which supports the tray;

Fig. 8 is a perspective view of one of the perforated mats which go to make up the tray;

Fig. 9 is a perspective view of the protective flap; and

Fig. 10 is a longitudinal cross-sectional view showing the manner in which the mats are inserted.

In illustrating one form of my invention, I have shown the same as comprising an outer casing generally indicated by the reference character 10, with the opposite small ends open. This outer 15 casing telescopically receives a tray-supporting casing or carton generally indicated by the reference character 11, as shown in Figs. 1, 2 and 3. This inner carton or tray holder is made of a single blank form, as shown in Fig. 7. This 20 blank comprises relatively long longitudinal sides 12 which are scored as shown at 13 and 14 so as to form bottom portions 15, which when folded in the proper form, are glued together so as to form a bottom of the tray holder. This tray holder, 25 as shown in Fig. 7, has a rectangular cut-out portion as shown at 15'. Adjacent the opposite ends of this cut-out portion 15' are tongues 16 which are scored along two spaced-apart parallel lines 17 and 18 for the purpose hereinafter described. The tray holder blank is provided with the usual end tongues 19 which are scored, as shown at 20, and side tabs 21 to form substantially the conventional enclosed type of carton.

One of the essential and novel features of this 30 35 carton construction includes a novel form of tray which is made of a series of perforated mats arranged one on top of the other so that the apertures therein are held in registering alignment by the tray holder or carton so that it does not become necessary to glue these perforated mats together as has been required heretofore where laminated cardboard mats of this type have been used. The perforated mats in this instance comprise substantially rectangular cardboards 40 generally indicated by the reference character 22, in Fig. 8 of the drawing. These mats are provided with a plurality of perforations 23 which may be any form or shape in order to accommodate the particular article or capsule 45 contained therein. The dimensions of these perforated mats are substantially those of the inside dimensions as to length and breadth of the completely folded tray holder 11 so as to fit snugly therein. In the present instance there are 50 55

three mats 22 of this type, as shown in Figs. 2, 3, 5, 6 and 10 of the drawing. The top perforated mat 24 is of the same dimensions as the other mats except that it is thinner and better material. Mounted below the perforated mats 22 and to act as fillers are two imperforate mats 25. The number of perforate and imperforate mats used in connection with this type of container depends entirely upon the size and shape of the article being merchandised and it will of course, be understood that any number of these mats, both of the perforate and imperforate, may be used. These perforate and imperforate mats are held against the bottom of the tray holder by the flaps 16 which are folded on the scored lines 17 and 18 as clearly shown in Figs. 2 and 7 of the drawing.

In assembling the tray and tray holder after the bottom portion 15 of the tray holder has been glued together, the flaps 16 are folded under the scored lines 17 and 18 while the tongues 19 on both ends of the carton are left open. The perforate mats 22 together with the imperforate mats 25 are arranged so that the edges thereof are all in alignment and one end of them are inserted through the top opening 15' of the tray holder and slid outwardly beyond one end in the manner shown in Fig. 10 of the drawing, after which they are all slid together to the right as viewed in this figure, so as to assume the position shown in Fig. 2. The flaps 19 are then folded or inserted to complete the tray and tray holder.

Another essential feature of the present invention involves the employment of a protective flap, generally indicated by the reference character 29 in Fig. 9 of the drawing. This protective flap is provided with a substantially rectangular opening 30 in which a transparent paper or cellophane 31 is glued to the bottom side of the flap. This flap 29 is scored on a transverse line 32 in substantially the center of the flap and is again scored adjacent one end thereof, as shown at 33, beyond which a tongue 34 extends. The tongue 34 is detachably inserted under one of the undeturned tongues 16 of the tray holder 11 so that when the telescoping cover 10 is partially removed to the position shown in Fig. 3 the free end of the flap 29 may be raised about the scored line 32. In this position, easy access to the articles within the tray may be secured. The primary function of this particular flap is to hold the articles, for example such as pills or capsules, within the recesses formed by perforations 23 of the mats 22 and 25 so that they will not be punctured or destroyed in the operation of telescopically closing the tray holder with respect to its outer covering 10. In this connection it will be noted that the external cover 10 is more or less of the conventional form of telescopic cover, but is provided with an opening on the top side thereof, as shown at 35, which is adapted to register with the window 30 for displaying the merchandise therein. From the above description it will be readily seen that I have provided a very simple and compact as well as a rugged type of carton of the partition or tray holder type in which all of the perforated mats necessary to form the partition for individual separation of capsules of the gelatin type or various other merchandise of fragile properties may be securely contained therein and dispensed therefrom without fear of destruction. The carton in this instance also protects the merchandise during the time that

the materials therein are being gradually dispensed. It will also of course, be understood, that these perforate blanks which go to make up the tray may be impregnated or otherwise treated with paraffin or other suitable substance so as to make them impervious to liquids if such is desired.

While in the above specification I have described one embodiment which my invention may assume in practice, it will of course, be understood that the same is capable of modification and that modification may be made without departing from the spirit and scope of the invention as expressed in the following claims:

What I claim is my invention and desire to secure by Letters Patent is:

1. A carton comprising a tray holder, a plurality of detachable perforated mats mounted in said tray holder, the adjacent mats contacting throughout their entire lengths and means for holding said mats in fixed position with respect to each other whereby the perforations forms recesses for merchandise.

2. A carton comprising a tray holder made of a single piece of cardboard, a plurality of perforated mats detachably mounted in said tray holder, said mats lying in contacting relation and means formed integrally with said tray holder and engageable with the upper mat for holding said mats against the bottom of said tray holder.

3. A carton comprising a tray holder, a plurality of similarly perforated cardboard inserts adapted to fit snugly into said tray holder for forming article-receiving recesses, end portions formed integrally with said tray holder and overhanging said inserts under-tucked flaps formed integrally with said end portions, said flaps being engageable with the uppermost insert for holding all of said inserts in compacted position, and a casing embracing said inserts and said tray holder.

4. A carton comprising a tray holder, a plurality of similarly perforated cardboard inserts adapted to fit snugly into said tray holder for forming article-receiving recesses, end portions formed integrally with said tray holder and overhanging said inserts under-tucked flaps formed integrally with said end portions, said flaps being engageable with the topmost insert for holding all of said inserts in compacted position against the bottom of said carton, and a casing embracing said inserts and said tray holder.

5. A carton comprising a tray holder, a plurality of perforated mats mounted in said holder, a plurality of imperforate mats mounted in said holder below said perforated mats, transverse end portions formed as a part of said tray holder and extending over said inserts and under-tucked flaps formed integrally with said end portions for urging all of said mats against the bottom of said tray holder.

6. A carton comprising a tray holder, a tray mounted in said holder, and a protective flap detachably secured to said tray holder and extending over said tray for protecting articles contained therein.

7. A carton comprising a tray holder, a tray mounted in said holder having a plurality of spaced-apart recesses therein for containing articles therein, and a transversely scored protective flap detachably secured to one end of said holder whereby said flap may be raised for removing the articles therefrom.

8. A folding carton comprising a tray holder, a tray mounted in said tray holder, transverse portions formed integrally with said tray holder and

extending over said tray at the ends thereof and flaps formed integrally with said transverse portions and adapted to be tucked thereunder for holding said tray in position.

- 5 9. A carton comprising a tray holder, a tray mounted in said holder having a plurality of spaced-apart recesses therein for containing articles therein, a transversely scored protective flap detachably secured between said holder and tray
- 10 for protecting the articles contained in said carton, and a casing embracing said tray holder and said tray.
- 15 10. A carton comprising a tray holder, a tray mounted in said tray holder, and a protective flap associated with said tray holder and extending

completely over said tray for protecting articles contained therein.

11. A carton comprising a tray holder, a tray mounted in said tray holder, and a flexible protective flap associated with said tray holder and extending over said tray for protecting articles contained therein. 5

12. A carton comprising a tray holder, a tray mounted in said tray holder, a transversely scored protective flap associated with said tray holder 10 and extending over said tray for protecting articles contained therein, and a casing embracing said tray holder and tray.

EDWARD C. BERG. 15
